CLAIM

The ornamental design for an electronic control module for electric brake of towed vehicle, substantially as shown and described.

DESCRIPTION

FIG. 1 is a perspective view of a control module embodying my new design looking from the right front. FIG. 2 is a front elevational view of the module as shown in FIG. 1.

FIG. 3 is a top view thereof.

FIG. 4 is a left side elevational view thereof.

FIG. 5 is a bottom view thereof.

FIG. 6 is a right side elevational view thereof.

FIG. 7 is a rear view thereof.

FIG. 8 is a fragmentary cross-sectional view taken on line 8—8 of FIG. 2.
